(57) **CLAIM**

The ornamental design for a window covering with shade panels having free lower edges, as shown and described.

DESCRIPTION

FIG. 1 is a front perspective view of a window covering with shade panels having free lower edges in a closed position.

FIG. 2 is a rear perspective view of the window covering with shade panels having free lower edges of FIG. 1 in a closed position;

FIG. 3 is a left side elevational view of the window covering with shade panels having free lower edges of FIG. 1 in a closed position;

FIG. 4 is a front perspective view of the window covering with shade panels having free lower edges of FIG. 1 showing the window covering with shade panels having free lower edges in an alternative partially open position, it being understood that alternating shade panels, beginning with the second from the top, are located behind the shade panels that are above them when the window covering with shade panels having free lower edges is in the closed position;

FIG. 5 is a rear perspective view of the window covering with shade panels having free lower edges in the partially open position in the FIG. 4 view; and,

FIG. 6 is a left side elevational view of the window covering with shade panels having free lower edges in the partially open position shown in the FIG. 4 view.

The broken lines in the Figures are for illustrative purposes only and forms no part of the claimed design.
